ABSTRACT

A vane-type centrifugal machine is provided which is characterized in that rotor bearings and end seals are arranged directly in a set composed of the working compressor stages while, where this set mates with a cylinder encasing the set, seals are mounted for the purpose of hermetically sealing in the medium being compressed.

FIG. 3

VANE-TYPE CENTRIFUGAL MACHINE, MAINLY, HIGH-PRESSURE COMPRESSOR

The present invention relates to turbo-machines and, more particularly, it relates to vane-type centrifugal machines which can be used, for example, in centrifugal compressors or in high-pressure pumps.

Presently used for obtaining high-pressure working fluid are centrifugal compressors comprising working compressor stages combined in a detachable set, separated from each other by inter-stage seals and encased in a cylinder. In such known machines, the bearings mounting the machine rotor, as well as end seals serving to preclude the leakage of the working fluid from the compressor blading, are arranged outside the set.

Said known compressors suffer from a number of disadvantages. No provision has been made in them for direct control over gaps in the inter-stage seals. As a result, it is rather difficult to keep the gaps minimal, which brings about inter-stage leakages of the working fluid and, consequently, a reduced efficiency of the machine. Note should be made that this is especially true of machines featuring relatively great pressure differences between the compressor stages.

In addition, in said known compressors, deformations of the cylinder or of the end lids, occurring as a result of the internal pressure of the working fluid being compressed, are transmitted to the rotor bearings and end seals, thus reducing the reliability of operation of these units.

A principal object of the present invention is to provide a vane-type centrifugal machine featuring minimal gaps in the inter-stage seals and a high operational reliability of bearings and end seals.

This is accomplished due to the fact that the bearings mounting the machine rotor and the end seals serving to preclude the leakage of the working fluid from the machine blading are placed inside the set, thereby insuring a direct control of the gaps in the interstage seals and practically eliminating the effect of the cylinder deformation upon the performance of the bearings and end seals. For the purpose of hermetically sealing the medium being compressed, seals are provided at places where the set mates with the cylinder.

Said latter seals can comprise a system of annular spaces with sealing members, designed for the delivery and removal of the compressed and sealing media.

In addition, with a view toward compensating for the thermal expansion of the set, inside the latter on each of the elements serving to bind the disks of the compressor stage featuring the highest pressure of the working fluid, there may be mounted compensators of the thermal expansion of the set.

It is preferred that, with a view to a convenient assembly of the machine, the top half of the middle portion of the set be of a smaller length than the corresponding bottom half of the set and that, in the gaps formed between the top half of the set and the non-detachable end disks of the set, gauge members be placed.

A vane-type centrifugal machine manufactured in accordance with the present invention makes for a successful solution of the problems stated hereinabove.

The present invention will be more apparent upon considering the following detailed description of a preferred embodiment of the invention, due reference being had to the accompanying drawings, in which:

FIG. 1 shows diagrammatically a longitudinal sectional view of the compressor;

FIG. 2 shows a set of the working compressor stages complete with a detachable top half for control over gaps;

FIG. 3 is a connection diagram of seals (units A) shown in FIG. 1; and

FIG. 4 shows unit B of FIG. 1, on an enlarged scale.

Referring now to FIGS. 1 and 2 of the drawings, the 10 centrifugal compressor described by way of example comprises a cylinder 1 which accommodates bottom and top halves 2 and 3, respectively, of the set of the working compressor stages. The set incorporates a rotor 4, stator blading elements 5 mounted between 15 disks 6 of the set, inter-stage seals 7, bearings 8 of the rotor 4, end seals 9 arranged in non-detachable end disks 10. The set is retained in the cylinder 1 with the aid of a pressure stop 11.

Placed between the top half 3 of the set and the non-detachable disks 10 are gauge members 12, while in places where the set mates with the cylinder 1 there are provided seals (units A) designed for hermetically sealing the medium being compressed.

During assembly, the rotor 4 is arranged on the bottom half 2 of the set on temporary supports with preset gaps along the inter-stage seals 7. Then are installed the non-detachable end disks 10 with the bearings 8 of the rotor 4, end seals 9 and other elements of the stator part of the machine. Following a final check of the gaps 30 along the interstage seals 7, the top half 3 of the set is installed. The assembled set is mounted in the cylinder 1 and fixed in place by means of the pressure stop 11.

The seal (unit A) comprises annular spaces 13, 14 and 15 (FIG. 3) and sealing members 16.

35 The spaces 13 communicate via channels 17 with the intake annulus of the machine (cavity of minimum gas pressure in the compressor), and via channels 18 with a closed reservoir (not shown) for collecting the leaks of the sealing medium. Supplied to the spaces 14 via channels 19 is a sealing medium under pressure slightly exceeding that in the space 13. This pressure difference is maintained automatically. Possible leaks of the sealing medium are drained to the spaces 15 and removed from the machine via channels 20. The sealing medium supplied to the space 14 is also used for hermetic sealing of the end seals 9 of the rotor 4.

In order to compensate for thermal expansion of the set, on each of elements 21 (cf., unit B in FIG. 1) serving to bind the disks of the stage featuring the highest pressure of the working fluid there are mounted compensators 22 of the thermal expansion of the set (FIG. 4).

When assembling the set, a gap a , equal to the value of thermal elongation of the set, is left between the surface 23 of the binding element and the bearing surface 24 of the disk of the set. The pressure stop 11 provides a preliminary force sufficient for a reliable retention of the set in the cylinder 1. With a pressure increase in the machine, the gap a is eliminated, and between surfaces 25 and 26 there forms a gap (shown with broken line in FIG. 4) sufficient to compensate for the thermal expansion of the set. Therefore, the thermal elongation of the set is not transmitted to the pressure stop 11.

65 What is claimed is:

1. A vane-type centrifugal machine adapted for constituting a high-pressure compressor, said machine comprising: a cylinder, a rotor, inter-stage seals, work-

ing compressor stages including blading and combined in a detachable set mating with said cylinder, said stages being separated from each other by said inter-stage seals and encased in said cylinder; bearings mounting said rotor within said cylinder and extending through said stages; end seals on said cylinder to preclude the leakage of working fluid from said blading; said bearings and said end seals being arranged directly in the set; and further seals to hermetically seal the medium being compressed, said further seals being mounted where said set mates with said cylinder, each said further seal comprising a system of sealing members with annular spaces being provided therebetween and adapted for the supply and removal of compressed and sealing media, said annular spaces including a first annular space communicated with the compressor cav-

ity of minimum gas pressure, a second annular space for the supply of a sealing medium and a third annular space for the drainage of the sealing medium, the second space being located between the first and third spaces and the mediums in the second space being at higher pressure than that in the first space.

5 2. A vane-type centrifugal machine as claimed in claim 1 comprising means for compensating thermal expansion inside the set.

10 3. A vane-type centrifugal machine as claimed in claim 1, wherein said set includes top and bottom halves and the top half of the middle portion of the set is of a smaller length than the corresponding bottom half of the set whereby there are formed gaps, comprising gauge members in the gaps.
